KITCHEN CABINET

Frank Weise, Philadelphia, Pa., assignor to Cornell Research Foundation, Inc., Ithaca, N. Y., a corporation of New York

Application March 12, 1954, Serial No. 29,496

Term of patent 14 years

(Cl. D33—19)

To all whom it may concern:

Be it known that I, Frank Weise, a citizen of the United States, residing at Philadelphia, in the county of Philadelphia and State of Pennsylvania, have invented a new, original, and ornamental Design for a Kitchen Cabinet, of which the following is a specification, reference being had to the accompanying drawing forming a part thereof.

The figure is a front perspective view of a kitchen cabinet showing my new design.

The side of the cabinet not shown is similar to the side shown and the back is plain.

I claim:

The ornamental design for a kitchen cabinet, substantially as shown and described.
